UNITED STATES PATENT OFFICE.

CHARLES E. DAUGHERTY, OF PORTLAND, OREGON.

LOOSE-LEAF BINDER.

1,257,982.

Specification of Letters Patent.

Patented Mar. 5, 1918.

Application filed August 10, 1916. Serial No. 114,171.

To all whom it may concern:

Be it known that I, CHARLES E. DAUGHERTY, being a citizen of the United States, residing at Portland, county of Multnomah, 5 State of Oregon, have invented certain new and useful Improvements in Loose-Leaf Binders, of which the following is a specification.

My invention relates to loose leaf binders 10 in general, and particularly to that class of such devices known as sales books or price books, in which the loose leaves are bound so as to enable the same to be turned over from one side to the other when the covers 15 are laid out flat, and which are designed to be carried in the pocket of a salesman.

Heretofore the leaves have been bound or secured within the covers of such books by means of circular rings passing through 20 perforations in the leaves, the objection to which construction is that said rings cause the back of the book to assume a semicircular shape which is cumbersome and inconvenient, results in much loss of space, and makes 25 a book wider than necessary for a given width of leaves.

The object of my invention is to overcome the above defects, and to produce a device which, while enabling the perforated leaves 30 to be easily attached and detached, or to be spread out flat, will conserve the waste space incidental to the use of said rings, and thus provide a book the width of which is a minimum for any given width of leaves to 35 be secured therein.

I accomplish the above object, and useful results, by means of the construction illustrated in the accompanying drawing, which therefore becomes a part of this application 40 for Letters Patent, and in which:

Figure 1 is a perspective view of a loose leaf book or binder embodying my invention, parts being broken away to best illustrate the construction.

Fig. 2 is a fragmentary plan view showing 45 one of the binding devices, with the covers laid open.

Fig. 3 is a sectional elevation upon line 3—3 of Fig. 2.

Fig. 4 is a detailed elevation, upon an enlarged scale, of one of the binding devices.

Like characters of reference indicate like parts throughout the various views of the drawing.

The book consists of a front cover 5 and a back cover 6 flexibly united by a back 7,

said front cover having flexibly secured thereto a flap 8, and said back cover having flexibly secured thereto a flap 9, between which flaps the leaves 10 are secured. 60

Pivottally attached to flap 9 are binding posts for the purpose of holding the loose leaves 10, the novel construction of which is as follows:

A flat bar 11 is pivotally attached to flap 65 9 by means of a screw 12, the end of said bar opposite said screw being turned up and slotted to form a hinge 13.

A post 14 integral with said bar 11 rises therefrom substantially vertically adjacent 70 said screw 12, the upper end of said post being curved in line with said bar and toward the hinged end 13 thereof, as shown at 14^a.

A post 15 is pivotally mounted within the 75 hinge 13, the upper end of which is curved to meet the end 14^a of post 14 when post 15 is substantially parallel to post 14, as shown at 15^a.

The end 15^a is provided with a tongue 16 80 which is adapted to enter a recess 17 in end 14^a, as shown in Fig. 4.

Post 15 is thus enabled to open into position 15^b for the purpose of enabling perforated loose leaves to be placed in position 85 with the post 14 passed through said perforations, and to be closed thereafter.

When the book is opened flat, as shown in Figs. 2 and 3, the leaves may be passed around and over the ends 14^a and 15^a from 90 position 10 to position 10^a, and vice-versa, as shown in Fig. 3, the binding posts then standing substantially parallel to one another and to the sides of the open book, as shown in Fig. 2. 95

When the leaves are all upon the post 14, or in position 10, and the book is to be closed, the binding posts may be rotated about pivotal screws 12 into a position shown at 18 in Fig. 2, and as illustrated in 100 Fig. 1, in which position the post 15 is immediately adjacent to the back edges of the bound leaves 10.

To hold the binding posts in position 18 I provide obliquely arranged slots 19 in 105 flap 8 which will coincide with the position 18 of the binding posts when the cover 5 is folded over upon the leaves 10, thus allowing the binding posts to be passed through the corresponding slots 19, as shown in Fig. 1. 110

As a means of locking the device in book form, and preventing the same from opening

out flat unless so desired, I provide hooks 20 pivotally attached to flaps 8 adjacent slots 19, each of said hooks being adapted to be passed over its adjacent slot beneath the closed ends 14^a and 15^a of the binding post, as shown in Fig. 1.

When thus securely locked closed the back 7 is brought into close juxtaposition to the back edges of the inclosed leaves 10, thus 10 eliminating the waste space heretofore occupied by the binding rings, and thus reducing the width of the book for any given width of leaves.

My invention may be made of any size and 15 constructed of any materials deemed convenient and suitable for a device of this character, and while I have illustrated and described a form of construction and arrangement of parts found desirable in materializing my invention, I wish to include 20 in this application for Letters Patent all mechanical equivalents or substitutes that may fairly be considered to come within the scope and purview of my invention as defined in the appended claims.

Having disclosed my invention so that others skilled in the art may be enabled to construct and use same, what I claim as new and wish to secure by Letters Patent is:—

30 1. In a loose leaf binder; a pair of covers;

a back flexibly connecting said covers; bars pivotally mounted within said covers; posts integral with said bars adjacent said pivotal points; posts pivotally mounted upon said bars, the ends of said posts meeting beyond 35 said bar to form an inclosure therewith, said bars being adapted to take an oblique position within said covers; and means within said covers to lock said bars in said oblique positions.

2. In a loose leaf binder having a pair of covers; oppositely disposed flexibly attached flaps within said covers; one of said flaps having obliquely disposed slots therein; 40 binding posts pivotally mounted upon one of said flaps opposite said slots; and hooks pivotally mounted upon one of said flaps adjacent said slots and adapted to lock said binding posts in place after same have been 45 passed through said slots.

In witness that I claim the foregoing as my own I hereunto affix my complete signature in the presence of two subscribing witnesses, at Portland, county of Multnomah, State of Oregon, this 4th day of July, 1916.

CHARLES E. DAUGHERTY.
